Primary Examiner — Darcey E Gottschalk(74) *Attorney, Agent, or Firm* — Dorothy S. Morse(57) **CLAIM**

The ornamental design for a thigh gap sculpting device, as shown and described.

DESCRIPTION

FIG. 1 is an exploded perspective view of a thigh gap sculpting device according to my new design;
FIG. 2 is a front view thereof, with the back view being a mirror image of that shown;
FIG. 3 is a side view thereof, with the opposite side view being a mirror image of that shown; and,
FIG. 4 is front view thereof in a position of use.
In the drawings, the broken lines depict environment that form no part of the claim.
